UNITED STATES PATENT OFFICE.

SAMUEL L. TUCKER, OF WOODBURY, NEW JERSEY, ASSIGNOR TO ARTHUR B. HUEY, OF PHILADELPHIA, PENNSYLVANIA.

SHEET-FEEDING MECHANISM.

1,202,333.

Specification of Letters Patent. Patented Oct. 24, 1916.

Application filed August 9, 1912. Serial No. 714,203.

To all whom it may concern:

Be it known that I, SAMUEL L. TUCKER, a citizen of the United States, residing at Woodbury, Gloucester county, State of New Jersey, have invented a new and useful Sheet-Feeding Mechanism, of which the following is a specification.

My present invention in its broad and generic scope consists of a novel sheet feeding mechanism wherein sheets of any desired material may be rapidly fed to any other desired mechanism adapted to operate on such sheets to produce articles of any desired nature and while in the present instance I have preferred to show my invention in conjunction with a printing press it will be evident that it is not limited to such use but may be employed in conjunction with any mechanism adapted to coöperate with a sheet.

It further consists of a novel sheet feeding mechanism wherein novel means are provided for supporting the pile of sheets as a sheet is withdrawn therefrom.

It further consists of a novel manner of mounting and actuating the sheet supporting table.

It further consists of a novel construction of a combined guide and stripper.

It further consists of a novel construction of a suction roll.

It further consists of a novel construction and arrangement of a sheet guiding plate.

It further consists of other novel features of construction, all as will be hereinafter fully set forth.

For the purpose of illustrating my invention, I have shown in the accompanying drawings those forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan view of a sheet feeding mechanism embodying my invention. Fig. 2 represents a sectional elevation

of Fig. 1. Fig. 3 represents a side elevation partly broken away of my device. Figs. 4, 5 and 6 represent sectional elevations of certain details of construction. Fig. 7 represents a side elevation partly broken away of my device. Fig. 8 represents a sectional elevation thereof. Fig. 9 represents a sectional elevation of certain of the parts seen in Fig. 8 but showing them in a different relation to each other. Fig. 10 represents a sectional plan view of a portion of the machine. Fig. 11 represents a sectional view of a portion of Fig. 9. Fig. 12 represents a perspective view of the stripper in detached position. Fig. 13 represents a sectional elevation of a portion of my device. Fig. 14 represents a sectional plan view of a portion of my device. Fig. 15 represents a plan view of another embodiment of my invention. Fig. 16 represents a side elevation of a suction roll showing another embodiment of my invention.

Similar numerals of reference indicate corresponding parts in the figures.

Referring to the drawings, since my invention relates more particularly to a sheet feeding mechanism I have deemed it unnecessary to illustrate or describe the entire printing press with which my invention is illustrated as being operatively connected since the construction and operation thereof will be understood by those skilled in the art.

1 designates the supporting framework in which is mounted the driving shaft 2, which is actuated in any desired manner and provided with a gear 3, meshing with a gear 4, mounted on a shaft 5 journaled in the frame 1.

The shaft 5 has fast thereon an eccentric sheave 6 that imparts, through its eccentric rod 7, a reciprocating motion to a plunger 8 fitted within the cylinder of pump casing 9. The cylinder 9 is pivoted at 10 in the supporting frame 1, as will be understood from Fig. 5, whereby said cylinder may turn on its pivot so as to assume the proper positions during the reciprocating movements of the piston 8.

The cylinder 9 is provided with a port 11 that forms a communication between the interior of said cylinder and the atmosphere, it being noted that said port 11 is

provided with a valve 12 normally seated against the same by the tension of a spring 13 whereupon when the plunger 8 is moving upward, air is drawn in the cylinder 9 through the opening 14 which is in communication with conduits 15, 16 and 17, so that air is drawn into the interior of the hollow suction feed roller 18 through the openings 19 as will be understood from Figs. 3, 4, 5, 8 and 9. The suction of air through the openings 19 draws the lowermost sheet of paper 20 or other material to be printed upon firmly against said feed roller 18 so that the sheet 20 is directed by the same through an opening 23 between the feed roller 18 and the inclined face of a plate or separator 24 to the feed rollers 25 and 26 which latter feed the sheet 20 through a combined guide and stripper 27 to the automatic grippers 28 in the press roll 29 which latter carries the sheet 20 to the printing or inking roll 30 and after passing between the rolls 29 and 30 is delivered to the endless apron 31 and table 32, see Fig. 7. The plate 24 may be adjusted relatively to the roll 18 by adjusting screw 92.

The pinion 3 meshes with a gear wheel 33 fast on a shaft 34 journaled in boxes 35 supported in the frame 1. The gear wheel 33 meshes with a gear wheel 36 fast on a shaft 37 so as to impart motion to the latter and consequently to the roll 29. The shaft 37 is journaled in boxes 38 supported in the frame 1. The shaft 37 has fast thereon the crank disks 39 that impart a reciprocating motion to the table 40 through links 41 which are pivoted at 42 to said disks 39 and hooked at 43 to pins 44 secured to the reciprocating table 40.

The table 40 has connected thereto, as at 45, one end of the apron 46 preferably constructed of fabric and whose opposite end is connected at 47 to one end of the springs 48 whose opposite ends are secured at 49 to a bracket 49, it being noted that each of said aprons 46 passes partly around the feed or suction roller 18 on opposite sides of the suction ports 19.

The table 40 is guided in ways 50 in the brackets 49 and 51 and reciprocates therein when the disks 39 are in motion. The brackets 49 and 51 are pivoted at 52, respectively, in the frame 1 so that said brackets may turn upon their pivots and thus permit the table 40 and its adjuncts to be swung away from the frame 1 whereupon access may be readily had to the interior of the machine for the purpose of inspection or repairs.

The frame 1 has pivoted thereto at 53 a link 54 provided with a slot 55 through which freely passes a pin 56 secured to the bracket 51, said link and pin serving to retain the bracket 51 and its adjuncts in their

outward positions as indicated in dotted lines in Fig. 7.

The table 40 has secured thereto a toothed rack 57 that engages a pinion 58 on the suction feed roll 18 so as to rotate the latter first in one direction and then in an opposite one in unison with the to and fro movements of the table 40.

The gear wheel 36 meshes with an idler 59, see Fig. 8, that is also in mesh with a gear wheel 60 on the feed roller 26 so that motion is transmitted from said gear wheel 36 to the feed roller 26 and also to a gear wheel 61 fast on the shaft 62 of said feed roller. The gear wheel 61 meshes with a gear wheel 63 fast on the shaft 64 of the feed roller 25 so as to impart motion thereto.

The disk 39 seen in Fig. 7 is provided with a cam member 65 adapted to rock an arm 66 secured to a shaft 67, it being noted that said arm has fitted therein a bar 68 adapted to be raised and lowered in said arm by an adjusting screw 69 so that by rotating the latter, said bar 68 may be raised and lowered in order to properly locate the toe 70 at the lower portion of said bar relatively to the cam member 65 so that said arm 66 may be rocked by the cam 65 at the proper time, it being apparent that when said bar 68 is in its uppermost position the cam member 65 will be brought in contact therewith later than if said bar were in its lowermost position.

When the cam member 65 is brought into contact with the toe 70, the shaft 67 is turned whereupon the arms 71 secured thereto and in which is journaled the feed roller 25 are moved upward or away from the feed roller 26 so as to release a sheet 20 of paper between them in order that the grippers 28 which take hold of the sheet 20 at this instant may readily carry the same around with the roll 29. The shaft 67 has fast thereon an arm 72, see Fig. 1, that operates with a spring 73 which latter acts as a buffer to prevent the feed roll 25 from rebounding when brought in contact with the feed roll 26.

The table 40 has secured thereto brackets 74 in which is journaled a shaft 75 which has secured thereto arms 76 provided with projecting members 77 adapted to support at certain times the forward portion of a stack of paper 20 when the lowermost sheet therein is being fed to the rolls 25 and 26 by the suction roll 18 and thus relieve said lowermost sheet of paper from the weight of those above it so that said sheet may readily slide from beneath the stack to the printing roll.

The shaft 75 has fast thereon an arm 78, see Fig. 13, to which one end of a spring 79 is secured, the opposite end of said spring being secured to any convenient fixed point as at 80, it being understood that the object

of said spring is to bring the arm 78 against the screw 81 that serves as a stop to limit the forward movement of said arm 78 as will be apparent from the position of the latter, as 5 illustrated in dotted lines in said Fig. 13. The shaft 75 has fast thereon an arm 82 adapted to turn the shaft 75 and the parts carried thereby when said arm 82 is brought into contact with an adjustable stop 83 supported in the bracket 51 so as to cause the arms 76 and projecting members 77 thereon to assume the positions seen in Fig. 13 so that the forward portion of a stack of paper 20 may readily slide upon the members 77 10 when the table 40 is approximately at the end of its forward movement.

The arm 66 has pivoted thereto one end of a rod 84, see Fig. 7, whose opposite end moves freely through a guide 85 in the bracket 51 and is provided with a collar 86.

87 designates a spring one end of which bears against the guide 85 while its opposite end bears against the collar 86 whereby the toe 70 is in contact with the disk 39.

25 The bracket 49 has secured thereto a disk 88 in which are adjustably fitted the lugs 89 and 90 that coöperate with the grippers 28 so as to open and close the latter at proper times in order to carry a sheet 20 around 30 with the roll 29 and also release it so that said sheet 20 may drop upon the delivery apron or belt 31. The roll 29 is also provided with fingers 91 that are adapted to throw a sheet 20 away from the roll 29 at 35 the proper time.

Since the grippers 28 and the fingers 91, as well as the mechanism for actuating the same may be of any well known type, it is 40 thought to be unnecessary to describe in detail such mechanism.

The brackets 49 and 51 are retained firmly in position on the frame 1 by hinged bolts 93 that engage slots 94 in said brackets and are provided with fastening nuts 95 that are 45 in threaded engagement with said bolts, it being understood that by loosening the nuts 95 and turning the bolts 93 on their pivots 96 so as to remove said bolts from the slots 94, the brackets 49 and 51 and their adjuncts may be brought into the position 50 seen in dotted lines in Fig. 7. The table 40 is provided with laterally adjustable guides 97 and 98, as best seen in Figs. 1 and 2.

55 It will be seen from Fig. 12 that the guide and stripper 27 is formed of a plate or bar 99 from which is spaced the plate 100 in order to provide an aperture through which the sheet being fed may pass. The ends of the plate 99 are deflected to form extensions 101 which are fixed in position in any desired manner. One side of the plate 99 is extended and deflected as at 102 to terminate in proximity to the roll 18 and is apertured or recessed as at 103, while the inner portion

of the plate 100 is upwardly deflected, as at 104, to terminate in close proximity to the feed roll 25, see more particularly Fig. 9, so that the sheet being fed is prevented from being carried around the roll 25 and is properly guided to the grippers 28.

In the suction roll seen most clearly in Figs. 1 and 10, the suction ports 19 are centrally located while in the embodiment seen in Fig. 16, I provide in proximity to each 75 end of the suction roll 105 enlarged bearings 106 and 107 having suction ports 108 and 109 respectively, whereby the suction acts on the sheet at three places instead of one. 110 is a feed roll having enlarged bearings 111, 80 112 and 113 in order to coöperate with the suction roll 105, seen in Fig. 16 in properly feeding the separated sheet through the machine. The separating or segregating plate 24 has its operative faces angularly inclined 85 as seen at 114 and 115.

The operation: The sheets to be fed are placed in a pile on the table 40 between the guides 97 and 98 and the driving shaft 2 is caused to revolve in any desired manner 90 thereby causing the gear 3 to actuate the gear 4 so that the pump 9 will create a suction on the suction roll 18 at predetermined intervals. The gear 3 through the medium of the gear 33 causes the gear 36 to revolve 95 thereby reciprocating the arms 41 and the table 40 connected therewith and which supports the pile of sheets. As the table 40 moves forwardly into the position seen in full lines in Fig. 13, it will be seen that the 100 forward portion of the pile of sheets is supported on the flexible aprons 46 which are retained in proper position by the tension devices 38. A suction has now been created in the suction roll 18 so that the lower- 105

most sheet adheres to the suction roll 18, it being remembered that the suction roll 18 is continuously revolving through the medium of the gears 58, 60, 59 and 36. The sheet withdrawn from the pile now moves into 110 the position seen in dotted lines in Fig. 13, then into the position seen in Fig. 9, and it then passes into the position seen in Fig. 8, the stripper 27 having prevented it from adhering to the roll 25 between which latter and the feed roll 26 is has now passed so that the sheet is now ready to be engaged by the grippers 28. The cam 39 has now coöperated with the lever 66 to rock the shaft 67 thereby causing the roll 25 to be 115 released from its engagement with the sheet so that the latter may be transferred to a desired point of utilization, for example, the printing roll 30 may coact therewith at this time and the sheet is then carried to the 120 traveling table 31 and discharged therefrom to the support 32. The pile of sheets from which a sheet has been removed in the manner just described has during this time engaged with the supporting members 77, hav- 125 130

ing moved up the inclined face 114 of the separating plate 24 and the forward portion of the pile of sheets is raised above the sheet being withdrawn to facilitate the withdrawal thereof. The springs 79 cause the arm 78 to be brought back against the stop 81 so that the sheets are properly aligned for the next forward feeding movement of the table 40. On the rearward movement of 10 the table 40 the forward portion of the pile of sheets will be supported on the bands 46. As the table 40 moves rearwardly the arm 82 will engage the stop 83 and rock the shaft 75 so that the arms 86 are moved out 15 of engagement with the pile of sheets against the tension of the springs 79 when the table has reached its rearward position seen in Fig. 13 in full lines. By adjusting the stops 83 or 81 the operation of the arms 20 76 will be correspondingly varied. The separator 24 may be adjusted with respect to the suction roll 18 by means of the set screw 92. The time at which the feed roll 25 is released from engagement with the 25 separated sheet may be varied by adjusting the set screw 69. The working parts are rendered readily accessible by loosening the nuts 95 whereupon the entire feed table and its adjuncts may be swung upwardly and 30 rearwardly as will be understood by reference to Fig. 7. I have illustrated herein means electrically controlled for automatically moving the press roll 29 out of engagement with the impression roll 30 when 35 no sheet is being fed but since such automatic mechanism is not claimed herein I have deemed it unnecessary to describe in detail such construction in the present application.

40 The press roll 29 and the printing roll 30 are intergeared and upon the failure of a sheet to be fed, the throw out mechanism is automatically operated to separate the press roll and printing roll from each other 45 and move them out of printing engagement but their gears are not disconnected during the operation of the printing press.

It will now be apparent that I have devised a novel and useful construction of a 50 sheet feeding mechanism which embodies the features of advantage enumerated as desirable in the statement of the invention and the above description and while I have, in the present instance, shown and described 55 a preferred embodiment thereof which has been found in practice to give satisfactory and reliable results, it is to be understood that the same is susceptible of modification in various particulars without departing 60 from the spirit or scope of the invention or sacrificing any of its advantages.

Having thus described my invention, what I claim as new and desire to secure by Letters Patent, is:—

65 1. In a sheet feeding mechanism, a sheet

support including a flexible apron, sheet removing means disconnected from said apron and around which said apron passes, means to continuously revolve said sheet removing means without winding up the apron on the 70 roll, and devices to effect the relative movement of said sheet support and said sheet removing means.

2. In a sheet feeding mechanism, a sheet support including a flexible apron, a suction 75 roll around which said apron passes, a tension device for said apron, means for reciprocating said sheet support, and means for creating a suction in said suction roll.

3. In a sheet feeding mechanism, a sheet 80 support including an apron, a suction roll around which said apron passes, a tension device for said apron, feed rolls to which a sheet is fed by said suction roll, means for moving one of said feed rolls out of engagement with the paper at predetermined intervals, means for moving said sheet support relative to said suction roll, and a suction creating device connected with said suction roll.

4. In a sheet feeding mechanism, a sheet support including an apron, a suction roll around which said apron passes, a tension device for said apron, feed rolls to which a sheet is fed by said suction roll, a sheet 95 guide having a stripper member terminating in proximity to one of said feed rolls, means for moving one of said feed rolls out of engagement with the paper at predetermined intervals, means for moving said 100 sheet support relative to said suction roll, and a suction creating device connected with said suction roll.

5. In a sheet feeding mechanism, a sheet support including an apron, a suction roll 105 around which said apron passes, a tension device for said apron, feed rolls to which a sheet is fed by said suction roll, a sheet guide having a stripper member terminating in proximity to one of said feed rolls and 110 a guide member terminating in proximity to said suction roll, means for moving one of said feed rolls out of engagement with the paper at predetermined intervals, means for moving said sheet support relative to said 115 suction roll, and a suction creating device connected with said suction roll.

6. In a sheet feeding mechanism, a sheet support including an apron, a suction roll 120 around which said apron passes, a tension device for said apron, feed rolls to which a sheet is fed by said suction roll, a sheet guide having a stripper member terminating in proximity to one of said feed rolls and a guide member terminating in proximity to said suction roll, said guide being apertured to permit said feed rolls to engage a sheet, means for moving one of said feed rolls out of engagement with the paper at predetermined intervals, means for moving 125 130

- said sheet support relative to said suction roll, and a suction creating device connected with said suction roll.
7. In a sheet feeding mechanism, a sheet support including a flexible apron, a suction roll around which said apron passes, a tension device for said apron, reciprocating means for said support, a stationary separator, a rock shaft carried by the sheet support, sheet supporting arms on said rock shaft adapted to support the sheet pile after a sheet has been separated therefrom, actuating devices for said arms, and means for actuating said suction roll.
- 15 8. In a sheet feeding mechanism, a sheet support including a flexible apron, a suction roll around which said apron passes, a tension device for said apron, reciprocating means for said support, a stationary separator, a rock shaft carried by the sheet support, sheet supporting arms on said rock shaft adapted to support the sheet pile after a sheet has been separated therefrom, an adjustable stop for said shaft, a tension device to maintain said arms in normal position, a stationary stop, an arm carried by said rock shaft adapted to engage said stop, and actuating means for said suction roll.
9. In a sheet feeding mechanism, a sheet support including a flexible apron, a suction roll around which said apron passes, a tension device for said apron, reciprocating means for said support, a stationary separator, a rock shaft carried by said sheet support, sheet supporting arms on said rock shaft adapted to support the sheet pile after a sheet has been separated therefrom, an adjustable stop for said shaft, a tension device to maintain said arms in normal position, a stationary stop, an arm carried by said rock shaft adapted to engage said stop, means for adjusting the position of said stop, and actuating means for said suction roll.
- 45 10. In a sheet feeding mechanism, a sheet support, a rock shaft thereon, a suction roll, actuating means therefor, a stationary separator, arms having deflected ends carried by said rock shaft on opposite sides of said separator, an adjustable stop, an arm on said rock-shaft, resilient means for normally maintaining said rock-shaft arm against said stop, an arm on said rock shaft, an adjustable contact member in the path of said last named rock-shaft arm, and means for causing relative movement of said sheet support and said suction roll.
11. In a sheet feeding mechanism, a table, an apron secured thereto, a suction roll around which said apron passes, a spring having one end fixed and the other end secured to the free end of said apron, means for reciprocating said table, means for rotating said suction roll, a sheet separator above which the sheet pile is moved after a
- sheet is separated from the sheet pile, devices automatically actuated to support the forward portion of the sheet pile after it passes the suction roll, means for causing said devices to be disengaged from the sheet pile on the rearward movement of said table, and means for reciprocating said table.
12. In a sheet feeding mechanism, a sheet support including an apron, a suction roll in engagement with said apron, a tension device for said apron, feed rolls, a rock-shaft carrying one of said feed rolls, a bracket carried by said rock-shaft, an arm mounted in said bracket, a cam for actuating said arm to rock said rock shaft, means to reciprocate said sheet support, and actuating means for said suction roll.
13. In a sheet feeding mechanism, a sheet support including an apron, a suction roll in engagement with said apron, a tension device for said apron, feed rolls, a rock-shaft carrying one of said feed rolls, a bracket carried by said rock-shaft, an arm mounted in said bracket, a cam for actuating said arm to rock said rock-shaft, means for relatively adjusting said arm and bracket to vary the coöperation of said arm with said cam, means to reciprocate said sheet support, and actuating means for said suction roll.
14. In a sheet feeding mechanism, a frame, a bracket movably mounted thereon, locking devices for said bracket, a sheet support movably carried by said bracket, a suction roll mounted in said bracket, actuating means for said suction roll, and actuating means for said sheet support and detachably connected therewith.
15. In a sheet feeding mechanism, a sheet support including an apron, a suction roll in engagement with said apron, a tension device for said apron, feed rolls, a rock shaft carrying one of said feed rolls, a bracket carried by said rock shaft, an arm mounted in said bracket, a cam for actuating said arm to rock said rock-shaft, resilient means for retaining said arm in the path of said cam, means to reciprocate said sheet support, and actuating means for said suction roll.
16. In a sheet feeding mechanism, a frame, a bracket pivoted thereto, a link secured to said frame and having a slot, a stud carried by said bracket and engaging said slot, a sheet support mounted for reciprocation in said bracket, a suction roll carried by said bracket, actuating means for said suction roll, and actuating means for said bracket and including connecting members detachably connected with said sheet support.
17. In a sheet feeding mechanism, a suction roll having a plurality of enlarged bearings with suction ports therethrough and forming a plurality of sheet engaging portions, feed rolls in proximity to said suction

- 6
 roll, one of which feed rolls is provided with a plurality of enlarged bearings engaging in suitable relation with respect to the enlarged bearings of said suction roll, and means for feeding sheets to said rolls. 5
18. In a device of the character stated, a suction roll, a separator having an inclined face adjacent said roll and spaced therefrom, feed rollers adjacent said separator, and a combined guide and stripper comprising an upper and a lower plate, the edge of the lower plate extending below said separator and adjacent to the periphery of said suction roll and having a slot therein, in which the feed rollers operate, and the upper plate being spaced from the lower and having an edge terminating adjacent the periphery of the upper feed roller and at the rear of the same. 10
19. In a device of the character stated, a suction roll, a separator having an inclined face adjacent said roll and spaced therefrom, feed rollers adjacent said separator, and a combined guide and stripper comprising an upper and a lower plate, the edge of the lower plate extending below said separator and adjacent to the periphery of said suction roll and having a slot therein, in which the feed rollers operate, and the upper plate being spaced from the lower plate and having an edge terminating adjacent the periphery of the upper feed roller at the rear of the same, the said inclined face of said separator extending to substantially the said upper feed roller. 15
20. In an automatic paper-feeder, the combination of a reciprocatory feed-table, a rotative sheet-separating suction-roller having at least one suction-orifice, a gap being formed between said feed table and suction roller on the rearward movement of said feed table, flexible strips extending from the end of the feed-table to and around said roller at either side of said orifice, and retractile springs having their rear ends fixed below the feed table and their front ends attached to said strips, said strips being thereby held taut and constituting an extension of the feed-table to support a paper pile over the gap. 20
21. In a device of the character stated, a frame, a bracket pivotally mounted thereon, a sheet-support slidingly mounted in said bracket, means for retaining said bracket in operative and inoperative position, means for reciprocating said sheet-support, said means being detachably connected therewith whereby said bracket and said sheet-support may be swung outwardly on the pivot, and means for limiting the outward movement thereof. 25
22. In a device of the character stated, a reciprocating sheet-support, operative mechanism to which the material is fed from the sheet-support, means for reciprocating the 30
- said sheet-support adapted to be released from operative engagement therewith, and a support for the sheet-support pivotally mounted to be swung outwardly, when said reciprocating means is released from operative engagement with said sheet support, whereby said operating mechanism is accessible for inspection and repairs. 70
23. In a sheet feeding mechanism, a sheet support including a flexible apron, a suction roll disconnected from said apron and around which said apron passes, means to continuously revolve said suction roll without winding up the apron on said roll, devices to effect the relative movement of said sheet support and said suction roll, and means to create a suction in said suction roll. 75
24. In a sheet feeding mechanism, a sheet support including a flexible apron, having one end connected thereto, a suction roll disconnected from said apron and around which said apron passes, to thereby form an upper and a lower stretch, means connected with the other end of the apron to maintain the upper stretch thereof in substantially the same plane as the sheet support, means to actuate said suction roll, devices to reciprocate said sheet support, and means to create a suction in said suction roll. 80
25. In a sheet feeding mechanism, a sheet support including a flexible apron, sheet removing means disconnected from said apron and around which said apron passes to thereby form an upper and a lower stretch, means connected with said apron to maintain the upper stretch thereof in substantially a constant plane, means to actuate said sheet removing means, and devices to effect the relative movement of said sheet support and said sheet removing means. 95
26. In a printing press, the combination with an impression cylinder, an automatic sheet feeding mechanism delivering sheets to said cylinder comprising a pair of revolving feeding rollers, a reciprocating table for supporting a pile of sheets that project rearwardly over said table, an oscillating suction picker operated by said table for selecting a sheet from the bottom of said pile and directing it toward said rollers, and flexible supporting means for the projecting portion of said pile of sheets extending from the rear of said table to and around the suction picker axis and back to said table. 100
27. In a printing press, the combination with an impression cylinder, an automatic sheet feeding mechanism delivering sheets to said cylinder, comprising a pair of revolving feeding rollers, means between the impression cylinder and said rollers for driving the latter, a reciprocating table for supporting the pile of sheets that project rearwardly over said table, an oscillating suction picker operated by said table for 110
- 115
- 120
- 125
- 130

selecting a sheet from the bottom of said pile and directing it toward said rollers, and a plurality of tapes for supporting the projecting portion of a pile of sheets, each tape 5 fixed at one end toward the rear of said table and extending to and around the suction picker shaft, and from thence forward to be attached to the table at the other end.

28. In a printing press, the combination
10 with an impression cylinder, an automatic
sheet feeding mechanism delivering sheets
to said cylinder comprising a pair of re-
volving feeding rollers, means between the
impression cylinder and the feeding rollers
15 for driving the latter, a reciprocating table
for supporting a pile of sheets that project

rearwardly over said table, an oscillating suction picker operated by said table for selecting a sheet from the bottom of said pile and directing it toward said rollers, a 20 plurality of tapes for supporting the projecting portion of the pile of sheets, each tape fastened at one end to the rear of the table and extending to and around the suction picker shaft, and from thence forward 25 to be attached to the table at the other end, and resilient means between the end of each tape and its attachment to the table.

SAMUEL L. TUCKER.
